(57) CLAIM

The ornamental design for a pair of trousers, as shown and described.

DESCRIPTION

FIG. 1 is a front view of the pair of trousers according to the invention;

FIG. 2 is a rear view of the pair of trousers as shown in FIG. 1;

FIG. 3 is a side view of the pair of trousers as shown in FIG. 1; and,

FIG. 4 is a detailed view of the seat portion of the pair of trousers as shown in FIG. 1.

The broken lines illustrated on the drawing views represent stitching.
